UNITED STATES PATENT OFFICE.

EBENEZER HILL, OF SOUTH NORWALK, CONNECTICUT, ASSIGNOR TO THE HILL COMPRESSOR & PUMP COMPANY, OF NEW YORK, N. Y., A CORPORATION OF DELAWARE.

ROTARY PUMP-SEALING MEANS.

Application filed October 25, 1923. Serial No. 670,702.

To all whom it may concern:

Be it known that I, EBENEZER HILL, a citizen of the United States, residing at South Norwalk, in the county of Fairfield and State of Connecticut, have invented a new and useful Improvement in Rotary Pump-Sealing Means, of which the following is a specification.

This invention relates generally to rotary fluid pumps and more particularly to the type for pumping or compressing fluids which have a rotor containing a driving gear with internal teeth and a driven gear with a different number of external teeth, the latter gear being eccentrically mounted within the former gear and the teeth so intermeshing that the rotation of the gears compresses and discharges whatever fluid is admitted between the gear teeth.

20 Pumps of this character have been provided with a ported sealing plate and means for causing the discharge pressure of the pump to be so exerted on the plate as to force it against the faces of the rotor and gears and prevent leakage of the fluid being pumped across the ends of the teeth, and they have also been provided with means for causing the discharge pressure of the pump to be so exerted on the back of the rotor as 30 to press the rotor and gears forward against the sealing surfaces whereby the wearing surfaces have been sealed according to the pressure produced by the pump.

The object of the present invention is to 35 arrange means in pumps of this nature by which in a simple manner the sealing engagement of the wearing surfaces and the amount of wear can be effectively controlled, which means cheapen the construction and 40 so act as to automatically take up all wear that may occur, and can be inexpensively and quickly refitted should the wear become excessive as a result of long and hard use.

This object is attained by placing a metal 45 wearing ring in the pumping chamber around the outside of the edge of the rotor in such position that the outer edge of the ring will be in the same plane as the outer edge of the rotor and the exposed faces of 50 the gears, whereby the sealing plate will bear against these elements equally and the wear on the parts will be uniform.

In the accompanying drawings Figure 1 shows a longitudinal section of a pump constructed according to this invention. Fig.

2 is a detail on larger scale showing the manner in which the sealing and wearing parts engage. Fig. 3 shows a face view of the pump with the head removed and a portion of the sealing plate broken away. Fig. 4 is 60 a section on the plane indicated by the dotted line 4—4 on Fig. 1.

The casing 1 is generally cylindrical in transverse section and it has a head 2 secured in such manner that it may be removed to give access to the interior of the casing. In one side of the casing shown is an intake opening 3 and in the other side of the casing is a discharge opening 4. The intake opens opposite the intake port 5 in 70 the sealing plate 6, while the discharge communicates with a passage 7 in the head that opens opposite the discharge port 8 through the sealing plate.

The cylindrical rotor 9, which is fitted in 75 the pumping chamber 10 so that it may have a longitudinal as well as a rotary movement therein, has a hub 11 that is supported by anti-friction bearings 12. The driving shaft 13 is splined to the rotor hub so that it 80 will turn the rotor without obstructing its longitudinal movement. A stuffing box 14 is arranged to prevent leakage about the shaft from the chamber 15 back of the rotor.

Secured to the rotor is a gear 16 with 85 internal teeth. In this gear and meshing therewith is a gear 17 with external teeth. These gears have a different number of teeth and the inner gear is mounted on a stud 18 with interposed anti-friction bearings 19. This stud is adjustably clamped in the sealing plate by nut 20, and its axis is eccentric to the axis of the driving shaft, so that the inner gear will be eccentric to the outer gear, as is well understood in pumps 90 of this class.

In a recess in the pumping chamber and encircling the outer edge of the rotor is a ring 21. This ring is made so wide that its outer face will be in exactly the same plane 100 as the outer end of the rotor and the exposed faces of the intermeshing gears.

The sealing plate has an axial movement in the chamber in the casing toward the rotor, gears and sealing ring, being normally 105 pressed against the faces of these parts by a spring 22. The outer end of the sealing plate is preferably provided with packing rings 23 that fit the circular inner wall of the chamber. The discharge port 8 in the 110

sealing plate is desirably elongated and is positioned so as to extend at the sides of the gears adjacent to the locality where the teeth bottom, while the intake port 3 in the sealing plate is shown as having a plurality of openings opposite the locality where the crests of the teeth of the gears contact. (Fig. 3). The chamber 15 back of the rotor has a connection 23 leading from the receiver 24 into which the fluid compressed by the pump passes from the discharge.

With the construction described discharge pressure is admitted to the chamber 15 and is exerted on the back of the rotor so as to tend to force the rotor and the gears forward, and discharge pressure filling the space in a chamber in front of the sealing plate forces the sealing plate backward against the rotor, gears and sealing ring. When the pump is starting up and there is no discharge pressure the sealing plate is pushed up against the sealing ring and the faces of the gears by the spring. As the pressure builds up, it forces the sealing plate back against the sealing ring and the rotor and gears, and coincidentally forces the rotor and gears forward against the sealing plate. If there is any wearing friction either the sealing plate or the gears will be slightly worn, and as the sealing ring will hold the plate in a definite position, in case any wear take place on either part, the pressure against the sealing plate will push the sealing plate against the ring, and the pressure back of the rotor will push the rotor and gears against the sealing plate. The amount of wear in any event is extremely slight, but it practically ends as soon as the parts are worn so that the edge of the ring and the edge of the rotor and the faces of the gears are in the same plane. If it is desirable to bring the sealing plate in a closer proximity to the faces of the gears all that it is necessary to do is to remove the ring and polish it so as to remove a fraction of a thousandth of an inch of its width and then reinsert it. With this simple construction the sealing engagement of the parts and the amount of friction, and consequently the extent of wear, is under exact control.

The invention claimed is:—

1. A rotary pump having a casing containing a chamber, co-acting pumping members rotatably mounted in said chamber, a sealing ring removably located in the chamber and encircling the pumping members, a plate axially movable in the chamber, and means whereby said plate is pressed against the pumping members and said ring.

2. A rotary pump having a casing containing a chamber, co-acting pumping members rotatably mounted in said chamber, a sealing ring removably located in the chamber and encircling the pumping members,

a plate axially movable in the chamber, and a spring pressing said plate against the pumping members and said ring.

3. A rotary pump having a casing containing a chamber, co-acting pumping members rotatably mounted in said chamber, a sealing ring removably located in the chamber and encircling the pumping members, a plate axially movable in the chamber, and means permitting fluid pressure to be exerted on said plate and force it against the pumping members and said ring.

4. A rotary pump having a casing containing a chamber, co-acting pumping members rotatably mounted in said chamber, a sealing ring removably located in the chamber and encircling the pumping members, a plate axially movable in the chamber, a spring pressing said plate against the pumping members and said ring, and means for admitting fluid pressure against said plate and supplementing the pressure of the spring.

5. A rotary pump having a casing containing a chamber, co-acting pumping members rotatably mounted in said chamber, a sealing ring removably located in the chamber and encircling the pumping members, a plate axially movable in the chamber, means pressing said plate against said ring, and means whereby the pumping members are pressed against said plate.

6. A rotary pump having a casing containing a chamber, co-acting pumping members rotatably mounted in said chamber, a sealing ring removably located in the chamber and encircling the pumping members, a plate axially movable in the chamber, and means for admitting discharge pressure to each end of the chamber and causing it to be exerted in opposing directions so as to force the pumping members and plate toward each other.

7. A rotary pump having a casing containing a chamber, co-acting pumping members rotatably mounted in said chamber, a sealing ring removably located in the chamber and encircling the pumping members, a plate axially movable in the chamber, means adapted to press said plate against said ring, and means adapted to press said pumping members against said plate.

8. A rotary pump having a casing containing a chamber, co-acting pumping members rotatably mounted in said chamber, a sealing ring removably located in the chamber and encircling the pumping members, a plate axially movable in the chamber, a spring pressing said plate against said ring, means for admitting discharge pressure against said plate and supplementing the pressure of the spring, and means for admitting discharge pressure and forcing the pumping members against the plate.

9. A rotary pump having a casing con-

taining a chamber, a rotor and co-acting pumping gears rotatably mounted in said chamber, a sealing ring removably located in the chamber and encircling the rotor, a plate axially movable in the chamber, and means permitting fluid pressure to be exerted on said plate and force it against said ring.

10. A rotary pump having a casing containing a chamber, a rotor and co-acting pumping gears rotatably mounted in said chamber, a sealing ring removably located in the chamber and encircling the rotor, a plate axially movable in the chamber, a spring pressing said plate against said ring, means for admitting fluid pressure against said plate and supplementing the pressure of the spring, and means for admitting fluid pressure against the rotor and forcing it 15 and the gears against said plate.

11. A rotary pump having a casing containing a chamber, co-acting pumping gears rotatably mounted in said chamber, a sealing ring removably located in the chamber and encircling said gears, a ported plate 25 axially movable in the chamber, and means adapted to press said plate against said ring.

12. A rotary pump having a casing containing a chamber, a rotor and co-acting 30 pumping gears rotatably mounted in said chamber, a sealing ring removably located in the chamber and encircling the rotor, a ported plate axially movable in the chamber, means permitting fluid pressure to be 35 exerted on said plate and force it against said ring, and means for permitting fluid pressure to be exerted on said rotor and force it and the gears against said plate.

EBENEZER HILL.
